Des. 236,147
Patented July 29, 1975

236,147

PIN WHEEL FAN

Lester V. Molenaar, Box 777, W. Highway 40,
Willmar, Minn. 56201

Filed Jan. 25, 1974, Ser. No. 436,524

Term of patent 14 years

Int. Cl. D21—01

U.S. Cl. D34—15 AP

FIG. 1

FIG. 2

FIG. 3

FIG. 4

FIG. 1 is a front elevational view of a pin wheel fan showing my new design;

FIG. 2 is a right side elevational view thereof, the side opposite being a mirror image;

FIG. 3 is a rear elevational view thereof; and

FIG. 4 is an enlarged sectional view thereof taken along line 4-4 of FIG. 1.

I claim:

The ornamental design for a pin wheel fan, substantially as shown and described.
